MACHINE FOR FORMING SOLID CARBON DIOXIDE

Reuben Hill, Los Angeles, Calif., assignor to Leo M. Harvey, La Canada, Calif.

Application November 29, 1937, Serial No. 177,048
Renewed June 23, 1939,

17 Claims. (Cl. 62—121)

This invention relates to machines for forming solid carbon dioxide.

In order to maintain refrigeration of a container, and more particularly one requiring transportation, it is a common practice to dispose the container in a packing formed by blocks or fragments of ice or of solidified carbon dioxide. Such practice consumes considerable time in preparing and positioning such packing, and the interstices between the blocks or fragments, and between the packing and the container materially detract from the refrigerant effect and also reduce the hold-over interval or period of refrigeration.

An object of the invention is to provide for solidifying carbon dioxide, as a continuous mass, in intimate and continuous contact with a container, so as to cool the latter with a maximum efficiency and offer a maximum resistance to sublimation.

Another object is to provide a machine for depositing a jacket of solid carbon dioxide in a substantially surrounding relation to a container, imposing a very low temperature upon the container and its contents, and eliminating the time and labor required in prior methods of applying refrigerant packings, and minimizing required refrigerant.

Another object is to form a refrigerant space between an inner and an outer container, and to provide for the delivery of liquid carbon dioxide to such space, and the consequent formation therein of a jacket of solid carbon dioxide for maintaining a prolonged low temperature cooling of the inner container.

A further object is to provide for a ready removal of the inner container from the outer one, to facilitate loading or unloading of the inner container.

A further object is to provide a machine comprising an enclosure wherein a container may be jacketed with solid carbon dioxide, said machine comprising, valve mechanism for controlling the flow of fluid carbon dioxide to such enclosure.

A further object is to provide for a discharge from such chamber in gaseous form, of such carbon dioxide as fails to solidify, and to utilize such gaseous carbon dioxide in precooling liquid carbon dioxide delivered to said chamber.

These and various other objects are attained by the construction hereinafter described, and illustrated in the accompanying drawings, wherein:

Fig. 1 is a view of the improved machine in side elevation.

Fig. 2 is an isometric view of a package, comprising inner and outer containers, showing the inner one partially withdrawn from the outer.

Fig. 3 is a cross sectional view, taken on the line 3—3 of Fig. 1, and showing said containers, as inserted in a receiver stationary on the machine.

Fig. 4 is another isometric view of said package, as seen from the rear.

Fig. 5 is a cross sectional view, taken on the line 5—5 of Fig. 1, showing valve mechanism controlling the flow of liquid carbon dioxide.

In these views, the reference character 1 designates a rectangular receiver, adapted to form an enclosure for a package or receptacle comprising inner and outer containers 2 and 3, which are also preferably rectangular. Said receiver and the outer container are formed preferably of a heat insulating material such as are common, and the inner container is formed of sheet metal, sufficiently thin to readily transmit heat. Doors 4, 5, and 6 serve to give access to the front ends of the receiver 1, and to the inner and outer containers, said doors being preferably hinged and equipped with suitable latches. The outer container preferably has a free sliding fit within the receiver 1, whereas the inner container is of materially smaller dimensions than the outer one, so that each of its walls may occupy a considerable spaced relation to the corresponding wall of the outer container. For establishing such relation, angular spacer strips 7, formed preferably of wood, or other material of low heat conductivity, are interiorly secured to the outer container at the intersections of its side and top walls, and spacer blocks 8 are interiorly attached to the door and rear wall of such container. Said strips and blocks are preferably so proportioned as to provide for equal spacing of all walls of the two containers.

For delivering liquid carbon dioxide into the space between the containers 2 and 3, one or more nozzles 9 are carried by and forwardly project from a circular manifold 10, exteriorly secured to the rear wall of the receiver 1, four of such nozzles being preferably employed, as illustrated. These nozzles pass snugly through the receiver 1, and project through oversize openings 11 in the rear wall of the container 3, so as to freely extend some distance between the side walls and top and bottom walls of the two containers. Liquid carbon dioxide is delivered to the manifold through a coil 12 from an expansion chamber 13, and a delivery connection 14 to said chamber leads out of a housing 15 for valve mecha-

nism controlling the flow. It is preferred to further employ said housing as a base for the receiver 1, and to enclose the manifold 10, coil 12, and expansion chamber 13 in a hood 16, 5 formed of heat insulating material, and preferably mounted jointly on the rear end portions of the receiver and said housing.

Valve mechanism within the housing 15 (see Fig. 5) comprises a base plate 17, a valve casing 18 carried by such base plate, a valve member 19 controlling flow through said casing, a lever 20 pivoted on the base plate at 21 and effective at one end on the needle valve, a spring-pressed plunger 22 bearing on the other end portion of 15 said lever, and tending to close the valve, and a lever 23 for opening the valve, pivoted on the base plate and rigidly carrying at its pivotal axis a pinion 24, meshing with a rack bar 25, slidably guided on the base plate. An end portion of said 20 rack bar is slotted lengthwise to accommodate a pin 26 carried by the lever 20, said slot permitting the rack bar and its actuating lever to be returned immediately by a spring 27 to a normal position, after the valve member 19 has been 25 fully unseated. For holding the valve member unseated, a latch arm 28, pivoted at 29 on the base plate, is formed with a sear 30 and is acted upon by a spring 31, serving to engage the sear 30 with a sear 32 on the lever 20, on shifting of 30 the latter to its valve-opening position. It is preferred to form the latch arm with an extension projecting through an opening 33 in the housing 15, said extension serving as a trip arm to permit of manual unlatching of the valve member, if 35 desired. The opening 33 also serves to allow the actuating lever 23 to project from the housing 15 to permit of its convenient manipulation.

The valve mechanism further comprises a device, mounted on the base plate 17 for automatically tripping the latch arm 28, after a predetermined lapse of time, to permit closing of the valve. As disclosed in Fig. 5, this device employs a plunger 34, operatively engaged, at its mid portion by one end of a lever 35, whereof the 40 other end is operatively connected by a link 36 to an arm 37 on the actuating lever 23. Such connection is preferably established by engaging a pin 38 on said arm in a slot 39 of the link, thus avoiding interference with automatic recovery by 45 the lever of its normal position, following a valve-opening control. The lever 35 is pivoted between its ends on the base plate, as indicated at 40 and carries, between its pivot and link-engaging end a roller 41, adapted to coat with the spring- 50 pressed end portion of the latch arm 28 to trip the latter, responsive to a certain rocking of such lever. One end of the plunger 34 is under pressure of a coiled spring 42, whereby a piston 43 on the other end of said plunger and working in a 55 dash-pot cylinder 44, is urged toward an end wall of such cylinder. Adjoining such cylinder is a chamber 45 from which a restricted passage 46 opens through said end wall, the degree of restriction being preferably regulable by a metering pin 47. A suitable liquid, preferably oil, occupies the space between the piston 43 and said cylinder end wall and also fills the chamber 45, at least to the level of the passage 46. Upon retraction of the piston from said cylinder end wall, 60 liquid may be freely drawn into the cylinder from the chamber 45, by way of a port (Fig. 5) controlled by a check valve 48, spring-pressed to resist outflow. Approach of the piston to the cylinder end wall imposes a pressure on the liquid in 65 the cylinder that supplements the check valve 70 75

spring in seating the check valve. Consequently the piston may not approach the cylinder end wall faster than the trapped liquid escapes through the passage 46.

While any suitable source of liquid carbon dioxide may be employed, it is preferred to cradle a tank 49 of such liquid on a stand 50 which mounts the machine at a convenient elevation. Such tank is terminally provided with a valved fitting 51 from which a delivery connection 52, 10 preferably flexible, leads to the valve casing 18.

To cradle said tank, as described, it is preferred to invert the tank and engage its valved end with a recessed main support 53, which is apertured to accommodate the fitting 51, and is 15 equipped with a pair of opposed trunnions 54, journaled in cross bars forming a lower portion of the stand. When thus engaged with said main support, the tank may be readily tilted to laterally rest against a bar 55 terminally engaging a 20 pair of hooked keepers 56 carried by the stand above and to one side of the lower support. Mounting said bar in this manner permits of its ready detachment from the stand to facilitate installation or removal of the tank. 25

To carry off from the receiver 1 such gaseous carbon dioxide as fails to solidify, a duct 57 (Fig. 1), preferably of rubber or the like flexible material, is engaged with suitable fittings 58 and 59 respectively surmounting said receiver and 30 the hood 16. Gas failing to form snow escapes from the container 3 through the openings 11 and flows between said container and the receiver to the vent duct 57. As best appears in Fig. 4, a channel 60 may extend in the top wall of the 35 container 3 from the rear edge to the center portion of said wall, to facilitate the escape of gas. A vent 61 in the bottom of the hood 16 serves to discharge gas to the atmosphere. Since the gas thus passed through the hood is at very low temperature, it effectively precools the liquid carbon dioxide flowing through the expansion chamber 13 and coil 12. The chamber 13, in affording the carbon dioxide a limited expansion before reaching the nozzles, also exercises a precooling 45 effect, and the manifold 10 provides for a still further precooling, in affording additional expansion of the carbon dioxide. In case, for any reason, the described provision for a free escape of gas fails to function, the resultant buildup 50 of gas pressure will disengage the duct 57 from one or both of the fittings 58 and 59 to relieve such pressure.

Fig. 4 illustrates how the openings 11 in the receiver 3 may be closed by corks 62 or the like, 55 after removal of a charged package from the machine. This prevents access of relatively warm air to the charge of solid carbon dioxide, and retains in the package cold gas resulting from sublimation. In case gas accumulated in a pack- 60 age acquires any considerable pressure, one or more of the corks 62 will yield to relieve such pressure.

In operation of the machine, after insertion in the receiver of one of the packages comprised by 65 the containers 2 and 3, and after closing of the doors 4, 5, and 6, the lever 23 is downwardly rocked by the operator, until the sears of the latch arm 28 and lever 20 interengage to latch the valve member clear of its seat. This actuation of the 70 lever 23 is further effective, through the link 36 and lever 35, to shift the plunger 34 from its illustrated position (Fig. 5), to a position (not shown) compressing the spring 42 and shifting the piston 43 toward the open end of its cylinder. Such 75

travel of the piston draws a considerable charge of liquid into the cylinder, the check valve yielding to admit same. Upon release of the lever 23, the spring 42 immediately initiates a return travel of the plunger, and the time required to complete such travel is determined by the setting of the metering pin 47, since this controls the rate of liquid discharge from the cylinder. As the plunger completes its return travel, the roller 41 trips the latch arm 28, and the valve member is immediately seated, responsive to the spring-pressed plunger 22.

Thus it is seen that the valve mechanism is semi-automatic in its operation, the valve being manually opened, and automatically latched in open position, and closing of the valve occurring automatically upon a predetermined lapse of time.

Opening of the valve establishes a flow of liquid carbon dioxide to the nozzles 9, and in its discharge into the space between the containers 2 and 3, gasification of the liquid follows from relief of pressure. This change of form is productive of an intense cooling effect, resulting at once in a further transformation of the major portion of the carbon dioxide into snow particles. These adhere to the spaced walls of the two containers, rapidly accumulating thereon until the entire space is occupied by a mass of tightly packed carbon dioxide snow. The dash-pot timing device will be regulated to automatically cut off carbon dioxide delivery upon a time lapse, sufficient for formation of the described charge of snow.

When the machine is employed to refrigerant charge a considerable number of similar packages, of the type shown in Fig. 2, a regulation of the timing device to suit one thereof, suffices for all. Since the "holdover," or prolongation of refrigerant effect, is dependent on the volume of snow with which a package is charged by the machine, it follows that packages may be designed with different accommodations for snow, to predeterminedly differentiate their holdover periods. Adjustment of the metering pin 47 permits of readily regulating the period of carbon dioxide flow to conform with the charging capacity of any particular package or group of packages.

In event of failure of the automatic features of the machine, or if, for any reason, an operator desires to interrupt a package-charging operation, the exterior extension of the latch arm 28 permits of manually cutting off the flow of carbon dioxide.

The charging of packages with a refrigerant, as described, is useful in various ways. A package so charged assures maintenance of a predeterminedly low temperature within the inner container for a definite period, which may be predetermined to protect perishable commodities throughout shipment to a certain destination. The protective temperature may be above or below the freezing point of the commodities, according to the design of the package.

If it is necessary for a consignee to further prolong refrigeration of commodities delivered to him in a frozen or other refrigerated state, the machine readily permits of such prolongation.

Dehydration of commodities by the carbon dioxide is prevented by sealing of the former from the latter, within the inner metallic container.

While a rectangular package has been shown and described, it is apparent that the receiver may be designed to accommodate packages of any other shape.

The invention is presented as including all such modifications and changes as come within the scope of the following claims.

What I claim is:

1. A machine for forming solidified carbon dioxide comprising a chamber for receiving a package formed with a space for the reception of the refrigerant, a nozzle for discharging carbon dioxide into said space, a duct for delivering carbon dioxide to the nozzle, a valve controlling the nozzle, means normally urging the valve to its closed position, a latch operable to hold the valve open, a time controlled device for releasing the latch after a predetermined interval of time, and means for opening the valve operable to condition said device for operation. 5

2. A machine for forming solidified carbon dioxide comprising a chamber for receiving a package formed with a space for the reception of the refrigerant, a manifold at the exterior of the chamber, spaced nozzles communicating with the manifold and adapted to discharge into said space, a hood housing the manifold, a conduit 15 conducting carbon dioxide to the nozzles and passing through the housing, a valve controlling the conduit, and means for passing the carbon dioxide that fails to solidify in said space from the space to the hood to cool the carbon dioxide 20 25 in the conduit.

3. A machine for forming solidified carbon dioxide comprising a chamber for receiving a package formed with a space for the reception of the refrigerant, a duct for delivering carbon dioxide to said space to refrigerate the same, a coil interposed in the duct, a valve controlling the duct, and an automatic control mechanism for the valve. 30

4. A valve mechanism comprising a valve, a control lever for the valve, spring means acting on the lever to close the valve, a shiftable part for operating the valve, a latch releasably engageable with the part to hold the valve open, and time delay means for retardantly releasing 40 the latch. 35

5. A machine for forming solid carbon dioxide comprising a chamber wherein the solidification occurs, means for conducting fluid carbon dioxide to the chamber, a valve controlling the conducting means, means normally closing the valve, a latch for holding the valve open, a timing mechanism for releasing the latch after a predetermined time interval, and a common means for opening the valve and conditioning said timing 45 mechanism for operation. 50

6. A machine for forming solidified carbon dioxide comprising a chamber for receiving a package formed with a space for the reception of the refrigerant, said chamber having an admission opening through which the package may be inserted and withdrawn, a closure for the opening, a nozzle discharging in the chamber positioned to supply carbon dioxide to said space when the package is arranged in the chamber, 60 and means for conducting carbon dioxide to the nozzle. 55

7. A machine for refrigerating packages comprising a chamber for receiving a package, nozzle means for discharging fluid carbon dioxide into the package in the chamber, a line conducting carbon dioxide to the nozzle means, valve means controlling said line, means normally yieldingly closing the valve means, means for opening the valve means, and means made operative by 70 actuation of the last named means for delaying the closing of the valve means. 65

8. A machine for refrigerating packages comprising a chamber for receiving a package, nozzle means for discharging fluid carbon dioxide into 75

- the package in the chamber, a line conducting carbon dioxide to the nozzle means, valve means controlling said line, means normally yieldingly closing the valve means, means for opening the valve means, and dash pot means made operative by actuation of the last named means for delaying the closing of the valve means.
9. A machine for refrigerating packages comprising a chamber for receiving a package, nozzle means for discharging fluid carbon dioxide into the package in the chamber, a line conducting carbon dioxide to the nozzle means, valve means controlling said line, means normally yieldingly closing the valve means, operating means for opening the valve, time delay means for delaying the closing of the valve means, and an operative connection between the operating means and the time delay means conditioning the time delay means for operation when the valve means is opened and freeing the operating means for return upon conditioning of the time delay means.
10. In a device for forming solidified carbon dioxide, nozzle means for discharging carbon dioxide, means for conducting fluid carbon dioxide to the nozzle means, valve means controlling the conducting means, means normally yieldingly holding the valve means closed, releasable means for holding the valve means open, operating means for opening the valve means and putting the releasable holding means into operation, and time delay means for releasing the releasable holding means at the end of a predetermined interval of time.
11. In a device for forming solidified carbon dioxide, nozzle means for discharging carbon dioxide, means for conducting fluid carbon dioxide to the nozzle means, valve means controlling the conducting means, means normally yieldingly holding the valve means closed, releasable means for holding the valve means open, operating means for opening the valve means and putting the releasable holding means into operation, and time delay means for releasing the releasable holding means at the end of a predetermined interval of time, the time delay means including manually regulable means for varying said interval.
12. A machine for refrigerating a package comprising a receiver for the package, nozzle means for discharging carbon dioxide into the package when the package is in position in the receiver, a line conducting fluid carbon dioxide to the nozzle means, means interposed in said line allowing partial expansion of the carbon dioxide, a housing enclosing said interposed means, and means for conducting the carbon dioxide that fails to solidify in the package from the package and receiver to said housing to have a precooling effect on the carbon dioxide in the line and said partial expansion means.
13. A machine for refrigerating a package comprising a receiver for the package, nozzle means for discharging carbon dioxide into the package when the package is in position in the receiver, a line conducting fluid carbon dioxide to the nozzle means, a coil interposed in said line, a housing enclosing the coil, and means for conducting the carbon dioxide that fails to solidify in the package from the receiver to the housing to cool the coil.
14. In a device for forming solidified carbon dioxide, discharge means for discharging the carbon dioxide, valve means for controlling the discharge means, means urging the valve means to the closed position, operating means for opening the valve means, releasable means for holding the valve means open, time delay means operable to release said releasable means after a given time interval, and means for restoring the operating means after operation.
15. A device for refrigerating a package having an inner container and an outer container arranged around the inner container to leave a space between the container, the device comprising a receiver having an opening for receiving and positioning the package, discharge means positioned to discharge carbon dioxide into said space when the package is positioned in the opening, and means controlling the discharge means.
16. A device for refrigerating packages comprising a receiver having a chamber for receiving a package, the chamber being shaped to cooperate with the package to hold the same in a given position, discharge means for discharging carbon dioxide into the package when the package is in the chamber, and a control for the discharge means.
17. A device for refrigerating packages comprising a receiver having a chamber for receiving a package, the chamber being shaped to cooperate with the package to hold the same in a given position, discharge means for discharging carbon dioxide into the package when the package is in the chamber, and a manually conditioned time governed control for the discharge means operable to cause the discharge of carbon dioxide for a given period.

REUBEN HILL.
